[57] CLAIM

The ornamental design for a marine ventilator fitting, substantially as shown and described.

DESCRIPTION

FIG. 1 is a left side elevation view of the marine fitting, the right side elevation view being the same;

FIG. 2 is an end elevational view of the fitting, taken on lines 2—2 of FIG. 1;

FIG. 3 is an opposite end elevational view of the fitting, taken on lines 3—3 of FIG. 1;

FIG. 4 is a top plan view of the fitting, taken on lines 4—4 of FIG. 1; and

FIG. 5 is a bottom plan view of the fitting taken on lines 5—5 of FIG. 1.

FIG. 3.

FIG. 4.

FIG. 5.
